UNITED STATES PATENT OFFICE.

HENRY W. SUMNER, OF SEATTLE, WASHINGTON.

AIR-SUPPLY SYSTEM FOR TWO-STROKE-CYCLE ENGINES.

Application filed September 17, 1925. Serial No. 56,866.

My invention relates to means employed for supplying air to internal combustion engines of the two-stroke cycle type, and also to the provision of space for containing the air compressed by the scavenging pump of such engines.

My invention consists in so constructing the frame of the engine as to provide therein suitable channels and storage spaces for the air which is compressed by the scavenging or air supply pump, whereby the provision of special containers outside of the frame may be avoided.

The drawings herewith illustrate the manner in which I have secured these results, the particular construction being illustrative of the principles employed.

Figure 1 is a transverse elevation of an engine having my invention embodied there-in.

Figure 2 is a side elevation, the same being partly in section, the section parts being approximately on the line indicated by the broken line 2-2 of Figure 1.

Figure 3 is a diagrammatic perspective of certain elements of the frame, illustrating the location and the manner of connecting the spaces in said frame in order to provide the air storage channels in which the compressed air delivered from the pump is stored until admitted to the cylinder.

Figure 4 shows in perspective a plate which is used as a valve for controlling the admission of air to the pump.

The type of engine with which my invention is intended to be used is the two-stroke cycle internal combustion engine. As herein illustrated this has a frame of the accepted marine type, that is, with inclined posts forming an inverted U. The particular construction of the piston, its cylinder, and the parts of the engine other than those specifically described, may be anything which is found to suitably fit with the parts which are the specific features of my invention.

The piston 1 is of the inverted skirt type. The cylinder 2 has an admission port 20 and an exhaust port 21. These are covered and uncovered by the upper edge of the piston after an accepted type of construction. The lower portion of the cylinder casting is enlarged and so connected with

the main frame as to form a chamber 22 which connects with the supply port 20 and with the lower open end of the cylinder 2. This chamber 22 also forms a cross connection between the two posts 3 and 30 of a pair.

The posts 3 and 30 are hollow and are used both as connecting passages between the air inlet valve and the pump, and as portions of the air storage space into which the air is compressed by the pump and held for a moment before being admitted to the power cylinder.

One of the posts of the frame, as the post 3, has an opening controlled by a valve 4. Connecting with this valve and exterior thereof is a hollow casting 40 which connects with a header 41, the latter extending lengthwise of the engine and connecting with all of the various cylinders for the purpose of supplying air thereto. At one end of the header an upward extension 42 is provided in which is mounted a damper or valve 43 by which the effective area of the opening may be controlled.

In carrying out my invention two power cylinders with their associated parts, including their separate frames, are linked together to form a single power unit. The engine may, however, be made up of two or more such power units. Each half of each unit is essentially a duplicate of the other half, the difference being this, that a single air compression pump is supplied for each two cylinder units, and the exact position and location of the spaces employed for the air storage reservoir varies slightly as between the two halves of the unit.

At or near the base of the post 30 which is at the opposite side of the engine from that which carries the air inlet valve, is connected the air compression pump. The cylinder 5 has a piston 50 therein and a rod 51 extending upwardly therefrom. This pump is double-acting. It is operated through a rock arm 6 mounted upon a pivot or fulcrum shaft 60 and at its other end connected with the cross head 62 by a short link 61. A similar short link 63 is employed for connecting the opposite end to the rod 51 of the air pump.

It will be noted that near the lower end of the post 30 of the engine frame is pro-

vided a partition or web 31 extending across the same. The upper end of the air pump connects with the upper portion of the chamber in the post 30 by a port 52, while the lower end of the air pump cylinder connects with the portion of said post below the partition 31 by a port 53.

That post at the front side of the engine which is opposite the one to which the air pump is directly connected communicates at its lower end with a passage or chamber 32 formed in a portion of the bed frame which extends parallel with the axis of the engine shaft. The portion at the bottom of the post 30 to which the lower end of the air pump connects is also connected with a corresponding chamber 33 formed in the engine base at the opposite side, that is, at the rear side of the engine. The other end of this chamber 33 connects with the other rear post 30 of the engine which is the companion in the engine unit. This latter post 30 connects with the corresponding chamber 32 at the lower end of the power cylinder 3 and with the post 3 which is a part of the same frame.

It is the purpose to have these chambers of such volume that they may serve as channels for the supply of air to the scavenging pump and also as storage chambers for the air compressed by the pump and also by the power piston in its downward movement. In order to balance the storage capacity into which opposite ends of the air pump discharge, I may provide intercepting or cut-off partitions or diaphragms as 55 which may be positioned at such point in the length of the post in which it is placed as to make the two storage chambers of equal volume. The same result may be obtained in part at least by varying the position of the diaphragm 31.

In Figure 3 has been shown a diagrammatic perspective of the engine post and frame for an engine unit. The portions thereof which are used as the air passages and storage chambers are indicated by the dash-and-dot lines employed. The single dash-and-dot line indicates that portion which is employed in connection with the lower end of the air cylinder, while the double dash-and-dot line indicates the portion employed in connection with the upper end of the air cylinder. By properly proportioning these chambers and with this properly locating the cut-off partitions, as 55 and 31, the capacity of the chambers employed may be balanced for the two cylinders of a power unit. It is evident, of course, that other means for equalizing the capacity of these chambers and also for increasing or decreasing them may be employed. By the above expedient the frame itself is used as the storage chamber for the compressed air and therefore the space

which would be taken by a separate air storage tank is available for other purposes.

What I claim as my invention is:

1. An internal combustion engine of the two-stroke cycle type having its engine units grouped in pairs, and an air pump for each pair, the frame and base having channels forming two air storage chambers communicating each with its respective cylinder and end of the air pump. 75

2. A two-stroke cycle internal combustion engine having its power cylinders, pistons and frames arranged in pairs, a double acting scavenging pump for each pair of engine cylinders, and operating connections for said pump from the power pistons, the frame posts and base members connecting posts of each pair of the engines being hollow and communicating to serve as communicating passages and pressure storing chambers for the engine operating air, diaphragms dividing said passages into two parts of substantially like volume, said posts of each engine communicating each with its respective power cylinder and having a valve controlled port communicating with the free air, one end of the scavenging pump discharging into the frame posts of one of its engines, and the other end into the frame posts of the other of its engines. 90

3. An internal combustion engine of the two-stroke cycle type composed of two cylinder units placed side by side, each cylinder having its own A-frame, piston and connected parts and a base common to both cylinder frames, each frame having a chamber enclosing the lower part of its cylinder, and hollow posts connecting with said cylinder enclosing chamber, the base having a hollow girder member at each side extending between the bases of the posts for both A frames, said base girders at one side of the engine communicating only with the hollow post of one cylinder and at the other side with the hollow post of the other cylinder, as an air inlet valve upon each of the posts at one side of the engine, an air scavenging pump at the opposite side of the engine having one end connected with the post for one A-frame and the other end with the longitudinal chamber in the base girder, said longitudinal base chamber communicating with the posts of the other A-frame. 100

4. An engine frame for internal combustion engines of the type employing an air pump to supply air under pressures above atmospheric, comprising an air pump, as A-frame for each cylinder, said frame having hollow posts forming the sides of the A-frame and serving as receivers for the compressed air, said passages having controlled communication at different times with the engine cylinder and with the pump, and a base for said A-frames having a hollow longitudinal member at each side, the base 110

sages thus formed at one side of the base communicating with the air pump to receive the discharge from one side of said pump, and with a post of one A-frame and at the 5 other side of the base connecting the posts of both A-frames.

5. An engine frame for internal combustion engines of the type employing an air supply under pressure, comprising an A-frame for each cylinder and grouped in 10 pairs, the posts of said A-frames being hollow and for each frame communicating at their upper ends with each other, and with their respective cylinders, the diagonally opposite 15 posts of each pair of A-frames having

a transverse diaphragm forming two separate chambers therein, and a base frame having a hollow longitudinal beam at each side forming communicating passages between the bases of the posts of the pairs at 20 their respective sides, one of the posts which have the transverse diaphragms being provided with a port at each side of the diaphragm adapted for connection with an air compression means, and the posts at the 25 opposite sides of the frame each having an air intake port and valve therefor.

Signed at Seattle, King County, Washington this 9th day of Sept., 1925.

HENRY W. SUMNER.
